UNITED STATES PATENT OFFICE.

RICCARD PUDELKO, OF ZUG, SWITZERLAND, ASSIGNOR TO LANDIS & GYR, A.-G., A JOINT-STOCK COMPANY OF SWITZERLAND.

MECHANISM FOR DRIVING AND CONTROLLING ELECTRICITY METERS.

Application filed April 11, 1927, Serial No. 182,949, and in Switzerland April 20, 1926.

The invention relates to means for driving and controlling electricity meters, and more particularly to means of protecting the electro-magnetically operated, energy-measuring means from disturbance or aberration due to the work of driving the energy consumption registering means.

Objects and advantages of the invention will be in part further set forth hereinafter, and in part will be obvious herefrom or may be learned by practicing the invention.

The invention consists in the novel parts, constructions, combinations and arrangements herein shown and described.

15 The accompanying drawings, herein referred to and constituting a part hereof, illustrate an embodiment and a practicing of the invention, and together with the description serve to explain the principles thereof.

20 Of the drawings:

Fig. 1 is an elevation, with parts omitted, of a mechanism embodying the invention;

Fig. 2 is a top plan, on line 2—2 of Fig. 1, with parts in section, and showing the registering mechanism, which is omitted from Fig. 1;

Fig. 3 is an enlarged, fragmentary elevation of parts near the upper, right-hand part of Fig. 1; and

30 Fig. 4 is a fragmentary, enlarged elevation looking from line 4—4 of Fig. 3 in the direction of the arrows; and

Fig. 5 is a fragmentary, enlarged detail of a core terminal adjustment.

35 The invention is directed primarily to obviating and preventing error-producing disturbances or aberrations in the measuring and recording of electric energy consumption, due to the friction and inertia of the mechanism of the meter and the consumption of energy in driving the same. This object is effected, broadly considered, by providing a 40 separate driving means for the registering mechanism, thereby removing the work of overcoming inertia, the mechanical energy consumed in driving and other detracting and disturbing factors from the electro-magnetically driven meter element, said element being thus mainly utilized in governing the speed of the meter disc or equivalent mechanism proportionally to the energy consumption of the circuit.

More particularly, I provide means for practicing it, whereby driving means, electro-magnetic or otherwise, are provided for the

registering mechanism, and separate electro-magnetically driven and controlled means are provided for governing the thus driven registering means in conformity or proportion to the electric-energy consumption of the 60 circuit. Thus the means for governing, but not driving, the registering means are freed from the disturbances due to or arising out of the work of driving the registering mechanism.

65 Another object of the invention is to remove other error-producing or measurement-disturbing actions or influences which may exist. For example, in many meters devices are provided for producing a supplementary 70 torque on the meter disc, or equivalent element, for instance, during the starting period of the current flow. One kind of device for effecting such a supplementary torque is usually called a "dispersion wing" or "start- 75 ing wing".

While such devices have been either essential or desirable with various meters, yet their use has been accompanied with certain unfavorable or disturbing results, such, for instance, as causing slippage of the meter disc, and when such supplementary torque-producing devices are employed, it is desirable to keep them of as low power consumption as possible. By my present invention, such devices, even when used, may be reduced in size or power to a minimum, as when the registering mechanism is separately or independently driven, such a device need only have sufficient power to overcome the inertia of the 85 meter disc shaft bearings.

80 My invention finds one of its most valuable applications in meters, or other energy-measuring devices, having registering devices of an extensive or complicated nature, such, for instance, as the registers of multiple tariff meters. My present invention makes it possible to obtain accurate and otherwise satisfactory performance with a very small supplementary torque in electrical measuring apparatus having such extensive or complicated 90 registering devices.

100 The supplemental or independent driving means, acting separately from the meter disc, or equivalent element for measuring the energy consumption, may be mechanically actuated, so far as concerns the main features of the invention, but is preferably electro-magnetically driven and is so shown and described in the present preferred embodiment. 105 110

Referring now in detail to the present preferred embodiment of the invention, illustrated by way of example in the accompanying drawings, a general structure of a meter is shown, many parts not relating to the present invention being omitted for the sake of clearness. As shown, a meter casing 1 has affixed to the interior thereof a frame 2, which supports a core 3, of any suitable form, and provided with series or current coils 4 and a pressure coil 5.

A meter disc 8 is mounted on a spindle or shaft 9, mounted in end bearings 11 and 12, carried by supports 13 and 14, supported on the frame 2. The connections from the meter disc shaft to the registering mechanism comprise a worm 19, formed on the shaft 9, and meshing therewith is a worm-wheel 20, mounted on and having its hub 21 fixed to a shaft 22, mounted in bearings 23 and 24, supported from the frame of the registering mechanism. A pinion 27 is fixed on the end of the shaft 22, which pinion meshes with a gear wheel 28 of the registering mechanism 29. The registering mechanism may be of any known or suitable kind adapted for the particular kind of meter and the conditions under which it is operated and the uses to which it is put.

In many electricity meters a device is employed for overcoming the friction and inertia of the meter in starting, such devices being usually styled a "dispersion wing" or "starting wing". Such a device may be used, if desired, in connection with the present invention, and is so shown in the drawing. In said embodiment a supporting member or bracket 31 of non-magnetic metal is supported by screws 32, threaded into the meter core. Fixed to this supporting member is a piece or wing 33 of magnetic metal, which serves to impart an initial torque to the meter disc during the early or low-current stage in the operation of the meter. So far as concerns the main features of the present invention, the use or omission of the starting wing or equivalent device is immaterial.

Referring now to the embodied form of means for driving the registering mechanism otherwise than through the ordinary meter disc, a disc 37 is mounted on and its hub 36 is fixed to the shaft 22 of the registering mechanism, this disc being of aluminum or other non-magnetic metal. The embodied form of means for electro-magnetically driving the disc 37 comprises an elongated core terminal or projection 38, fixed to the core at one end or pole of the pressure coil 5, this pole 38 terminating adjacent to one face of the disc 37. If desired, this pole may be provided with a positioning or adjusting device 39 (Fig. 5) whereby its position relatively to the disc may be varied to control the driving action upon the disc.

The co-operating core pole terminal or pro-

jection comprises a member 40 fixed to the meter core on the outer side of the pressure coil 5, and this member has its other end closely adjacent to the opposite side of the disc 37 from the core terminal 38. For the purpose of creating a torque component tending to rotate the disc 37, the core terminal 40 is provided with separated projecting ends 41 and 42, extending toward the disc 37. The projecting end 41 has a copper ring 43 mounted thereon, for the purpose of influencing the magnetic field so as to provide the required torque component for rotating the disc 37. It will be understood that so far as concerns certain of the broader features of the invention, the drive for the registering mechanism could be of some other form, as for instance a mechanical drive; the meter disc in such case also, being connected to control the speed of the register driving shaft proportionately to the energy consumption.

From all the foregoing it will be understood that mechanism has been provided realizing the objects and advantages hereinbefore set forth, together with other objects and advantages; and that changes may be made from the details of method and procedure and of the construction herein exemplarily shown and described, without departing from the principles of the invention and without sacrificing its chief advantages.

What I claim is:—

1. An electricity meter mechanism including in combination registering mechanism, a meter coil and its core, means driven thereby for driving the registering mechanism, a meter disc driven by the meter coil and core and connections whereby the meter disc controls the speed of the driving means for the registering mechanism proportionately to the power consumption.

2. An electricity meter mechanism including in combination registering mechanism, a driving shaft therefor, a meter coil and its core, means driven thereby for driving said shaft, a meter disc driven by the meter coil and core, and connections whereby the meter disc controls the speed of the driving means for the registering mechanism proportionately to the power consumption.

3. An electricity meter mechanism including in combination registering mechanism, a driving shaft therefor, meter coils, a disc on said shaft, core projections in driving relation to said disc, other core projections, a meter disc driven thereby, and connections whereby the meter disc controls the speed of the registering mechanism driving shaft proportionately to the power consumption.

4. An electricity meter mechanism including in combination registering mechanism, a driving shaft therefor, meter coils, a disc on said shaft, core projections in driving relation to said disc, other core projections, a

meter disc driven thereby, a shaft for the meter disc, and connections between the meter disc shaft and said registering mechanism driving shaft whereby the speed of the latter shaft is controlled proportionately to the power consumption.

5. An electricity meter mechanism including in combination current and pressure coils and cores, a meter disc and spindle driven thereby, a registering mechanism, supple-

mental projections of opposite polarity on the pressure core, a disc and spindle driven thereby and connected to drive the registering mechanism, and connections between the two spindles whereby the registering mechanism is driven proportionately to the speed of the meter disc.

In testimony whereof, I have signed my name to this specification.

RICCARD PUDELKO.
